Patented May 3, 1960

187,815

LATCH FOR DUTCH DOORS

Alfred C. Wilson, Northbridge, Mass., assignor to The H. B. Ives Company, New Haven, Conn., a corporation of Connecticut

Application December 11, 1959, Serial No. 58,639

Term of patent 14 years

(Cl. D50—5)

Fig. 1.

Fig. 2.

Fig. 3.

Fig. 1 is a front elevational view of a latch for Dutch doors embodying my new design, showing same in partly latched position;

Fig. 2 is a side elevational view looking toward the left in Fig. 1; and

Fig. 3 is a top plan view looking downwardly on Fig. 1.
The undisclosed side of the latch is substantially the same in appearance as the side shown.

I claim:
The ornamental design for a latch for Dutch doors, as shown and described.
